UNITED STATES PATENT OFFICE.

HUGH A. DANIEL, OF RONDOUT STATION, KINGSTON, NEW YORK.

SKYLIGHT.

No. 829,910.

Specification of Letters Patent.

Patented Aug. 28, 1906.

Application filed April 5, 1905. Serial No. 254,037.

To all whom it may concern:

Be it known that I, HUGH A. DANIEL, a citizen of the United States, residing at Rondout Station, Kingston, in the county of Ulster 5 and State of New York, have invented certain new and useful Improvements in Skylights, of which the following is a specification.

My invention relates to skylights, and has for its object to provide a skylight conforming, substantially, to the slant of the roof and provided with flashings forming weather-tight joints upon all sides.

A further object of my invention is to provide a skylight having a rafter-bar composed 15 of a single strip of sheet metal folded to form upstanding ribs, laterally-extending glass-supporting shoulders, and gutters upon each side and beneath the shoulders.

A further object of my invention is to provide 20 a skylight having a sheet-metal box formed to permit the discharge of moisture from the gutters upon the roof.

A further object of my invention is to provide 25 a skylight having a sheet-metal curb folded to form a glass-supporting shoulder with a flashing for attachment to the roof and a gutter communicating with the gutters of the rafter-bar.

A further object of my invention is to provide 30 a rafter-bar having a flashing adapted for connection with a vertical wall and a counterflashing disposed to cover the flashing of the rafter-bar and having a skirt adapted to bear upon the glass at a little distance 35 from the rafter-bar.

A further object of my invention is to provide 40 a cap composed of sheet metal folded longitudinally and proportioned to cover the upstanding rib of the rafter-bar and having skirts arranged to bear upon the glass.

A further object of my invention is to provide 45 a skylight having a ventilator disposed to open beneath an apron extending from the roof to and over a portion of the skylight.

A further object of my invention is to provide 50 a skylight having a cross-joint so designed as to be easily formed by any skilled sheet-metal worker and easily placed in position in the skylight in such a way as to insure that any condensation or leakage reaching the under side of the skylight will be carried over to and deposited in the gutters of the rafter-bars.

A further object of my invention is to provide 55 a skylight having a fastening for the caps protecting the tops of the rafter-bars so ar-

ranged that the caps can be secured to the upstanding rib of the rafter-bars by clips made of sheet metal so formed as to leave a space for the lower end of a bolt to fit inside 60 the clip and above the rafter-bar and with flanges turned down on the clip to fit closely to the upstanding rib of the rafter-bar and be tightly secured to same by soldering, by bolts, rivets, or other improved means. 65

With these and other objects in view the present invention consists in the combination and arrangement of parts, as will be hereinafter more fully described, shown in the accompanying drawings; and particularly pointed out in the appended claims, it being understood that changes in the form, proportion, size, and minor details may be made within the scope of the claims without departing from the spirit or sacrificing any of 75 the advantages of the invention.

In the drawings, Figure 1 is a top plan view of my improved skylight, arranged adjacent to and connected with a vertical wall rising above the roof and the skylight. Fig. 2 is a 80 view of my improved skylight in side elevation. Fig. 3 is a sectional view through the lower portion of a skylight, taken upon line 3 3 of Fig. 1. Fig. 4 is a transverse sectional view of my improved skylight, showing the 85 upper curb in cross-section and taken on line 4 4 of Fig. 1. Fig. 5 is a transverse sectional view of my improved skylight showing in cross-section the rafter-bar attached to a vertical wall and taken on line 5 5 of Fig. 1. Fig. 6 is a transverse sectional view of my improved skylight, showing a rafter-bar and flashing in cross-section as attached to a roof and taken on line 6 6 of Fig. 1. Fig. 7 is a 90 transverse sectional view showing in cross-section an intermediate rafter-bar and its cap and taken on line 7 7 of Fig. 1. Fig. 8 is a transverse sectional view showing in modified form the parts shown in Fig. 3 with the 95 apron arranged for connection with a metallic or composite roof. Fig. 9 is a transverse sectional view of my improved skylight, showing in modified form the parts shown in Fig. 4 with the apron arranged for attachment with a metallic or composite roof. Fig. 10 is a transverse sectional view of the curb of my improved skylight, shown in modified form with a ventilating-cover in connection therewith and shown beneath an apron extending from the roof to and upon the skylight. Fig. 11 is a transverse sectional view of a cross-joint adapted for use in connection with my 110

improved skylight when the length of the skylight is so great as to make two or more lengths of glass desirable. Fig. 12 is a transverse sectional view of my improved rafter-bar, shown in conjunction with a modified form of cap and means for securing the cap to the bar. Fig. 13 is a modified form of abutment, shown in cross-section and designed to take the place of the metal box shown in Figs. 3 and 8. Fig. 14 is a detail view in vertical section of a modified form of cap shown in Fig. 12 and the means for securing it to the bar.

Like characters of reference designate corresponding parts throughout the several views.

In its preferred embodiment my improved skylight is adapted for use upon and in connection with an inclined roof, as one composed of the rafter 1, upon which is disposed the usual sheeting 2 and shingles 3 or other form of exterior covering. The upper and lower edges of the skylight-opening may be provided with the usual header 4, extending perpendicular to the rafters and rigidly secured thereto. The framework of the skylight is preferably composed of sheet metal and comprises an upper curb having a flange 5 secured to the sheeting and beneath the shingles or other covering and adjacent the upper edge of the skylight-opening. The curb is provided with a glass-supporting shoulder 6 and an obliquely-disposed depending sheet 7, upon the lower edge of which is formed the gutter 8. This curb extends transversely entirely across the skylight-opening.

Transversely across the lower edge of the skylight-opening is disposed a curb parallel with the curb upon the upper edge of the skylight-opening. Below this curb at proper intervals are spaced closed boxes of sheet metal. The lower curb or abutment of the skylight is placed upon the roof in such a manner as to form the apron 10 and is folded for attachment to the header 4 or a molding 11, secured thereto, as by the lip 12. The sheet is then folded upon itself to form the gutter 13 and is continued and again folded to form the glass-supporting shoulder 14 and the glass-retaining lip 15. The boxes 9 are set within the folds of the sheet and in the angle between the gutter and the glass-supporting shoulder. Moisture-discharging openings are provided, forming communication from the gutter 13 to the boxes 9, and the boxes are provided with holes 17 at each side to permit the discharge of moisture upon the apron 10, the central box 9 having these holes at each side thereof and the side boxes having moisture-discharging openings only at the side nearest the central rafter-bar.

Between the upper curb and the lower curb rafter-bars are disposed for supporting the glass of the skylight. The central and inter-

mediate rafter-bars are composed of sheet-metal strips folded longitudinally to form upstanding ribs 18, which extend the entire distance from the upper curb to the lower curb. Each side of the sheet-metal strip is then folded outwardly to form the glass-supporting shoulders 19, then inwardly and downwardly, then outwardly and upwardly to form the gutters 20. The lower side of the rafter-bar may be finished by a sheet-metal strip 21, folded to conform to the shape of the gutters 20, with their edges turned over the upwardly-disposed outer edges of the gutters, as shown at Fig. 7 in cross-section. The upstanding rib 18 of the rafter-bar is covered by a sheet-metal cap folded longitudinally to pass over the rib 18 and having skirts 23 extending laterally upon each side. The cap 22 is placed over the rib 18, with the skirts 23 resting upon the glass 24, and is secured in position by bolts 25 or in any approved manner.

To support the glass along the side of the skylight adjoining the roof, a rafter-bar is provided, as shown in cross-section in Fig. 6, having a flashing 26 secured to the roof in the usual well-known manner of laying successive sheets between successive courses of shingles, slate, tiles, or other materials. In the case of a metal roof the metal roofing material is turned up to form the flashing, and in the case of a composite roof the flashing is nailed to the sheeting and covered with the composition, or it may be embedded in the layers of same. The flashing is then folded upwardly, as shown at 27, and again folded down over the upwardly-projecting rib 29 of the rafter-bar and hammered in close to the same. The rafter-bar is composed of sheet metal folded to form a rib 29 and a glass-supporting shoulder 30, perpendicular thereto. From the extremity of the glass-supporting shoulder 30 is suspended the gutter 31, and the opposite edge of the metal sheet is folded to conform to the shape of the lower side of the gutter 31, as at 32, and its extreme edge folded over the outer edge of the gutter. The rafter-bar has the downwardly-projecting flange 28 of the flashing turned down and hammered close to the upwardly-extending rib 29 of the rafter-bar, as shown, and a longitudinally-folded cap 33, disposed upon and above the flashing and rib and with the skirts 34 bearing upon the glass 24. The cap 33 is secured by the bolts 25 or in any other approved manner.

When the skylight is located adjoining a vertical wall arising above and beyond the skylight, a rafter-bar of sheet metal is provided having the flashing 35 secured rigidly to the wall, as 36, and folded to form a glass-supporting shoulder 37. To the inner extremity of the shoulder 37 is secured the depending gutter 38. Adjacent the upper edge of the flashing 35 a recess is formed in the

wall 36 and a counterflashing 39 cemented therein by the usual method of pointing. The counterflashing 39 is then folded downwardly to cover the flashing 35 and its lower edge formed into a skirt 40 to bear upon the glass 24.

The rafter-bars are placed in position by rigidly securing them to the upper curb and the plate forming the lower curb or abutment 10 and with the glass-supporting shoulders 19, 30, and 37 all in a plane with the glass-supporting shoulder 6 of the upper curb and 14 of the abutment or lower curb. The rafter-bars, curb, and abutment are so proportioned 15 that the gutters 8 of the curb and 53 and 56 of the cross-joints communicate and discharge moisture into the gutters 20, 31, and 38 of the rafter-bars, and proper communication is formed between the gutters for such 20 purpose. The lower extremities of the gutters 20, 31, and 38 are rigidly secured within the gutter 13 of the abutment or lower curb and so proportioned that moisture from the gutters of the rafter-bars is discharged into 25 the gutter 13 and through the moisture-discharging openings 16 into the boxes 9. It will be understood that the glass 24 is laid upon the glass-supporting shoulders in and secured by the usual putty or other approved 30 form of cement. Along the upper edge of the skylight-opening an apron 41 is secured to the sheeting beneath the shingles or other materials 3 and extends downwardly to and upon the glass 24. In case of a metal roof the 35 apron 14 may be secured to the metal of the roof by a fold, as shown at 42, or in any other well-known and approved manner, and the apron 10 along the lower side of the boxes may be likewise secured, as shown in Fig. 8. 40 Instead of the boxes 9 an abutment 43 may be provided, covered with a sheet of metal 44, folded into a similar gutter, glass-supporting shoulder, and upstanding lip. The weep-holes 15 drain through metal tubes 16, which are extended to pass through an abutment 43, and a hinged or swinging cover 45 is secured to the abutment and covering the outer ends of the moisture-discharging openings to permit the passage outwardly of moisture, but to prevent the passage of rain or 50 snow inwardly.

In case it is desired to ventilate the skylight a bearing-block 46 may be secured along the lower edge of the upper head 4 and the rafter-bars secured rigidly thereto by the im- 55 placement thereon of the lower portion of the gutters. A plate 47 may also be secured to the header 4 and the bearing-block 46 and secured rigidly to the rafter-bars by solder or 60 in other approved manner. The curb is secured to the rafter-bars at a little distance from the end, and a deflecting-plate 48 is folded to cover the upper extremity of the curb, as at 49, and bearing upon the rib 18 65 of the rafter-bars. To the upper extremity of

the plate 47 is hinged a damper 50, having a depending flange 51, proportioned and disposed to shut over and engage the upstanding fold 49 of the deflecting-plate 48. This damper drains any moisture which may collect on it into the channel 61 of the deflecting-plate 48, through which it escapes through holes 62, spaced at intervals. The apron 41 is carried downward and over the damper 50 and secured to the rafter-bar 18 above the cap 22, as by the bolt 52.

Where the length of the skylight is so great as to make it desirable to use two or more lengths of glass, a cross-joint may be provided composed of sheet metal extending 70 transversely between rafter-bars and formed with a gutter 53, registering with the gutters 20, 31, and 38 of the rafter-bar. The sheet is then folded at an angle to form the glass-supporting shoulder 54 and lap 55. A brace 80 member may also be provided with a gutter 56, registering with the gutters of the rafter-bars and having a supporting-brace 57 rigidly secured beneath the under surface of the glass-supporting shoulder 54. The lower 90 glass is laid upon the shoulder 57 in the usual putty or cement, and the upper glass likewise laid in putty or cement is placed on the glass-supporting shoulder 54, with the lap 55, as shown in Fig. 11, extending down over the 95 lower glass.

Instead of the bolts 25 passing directly and transversely through the fold of the cap and the rib of the rafter-bar, bolts 52, provided with angular portions, may be substituted. 100 A clip 58 may be secured to the rib of the rafter-bar and the angular portion of the bolt 52 passed through an opening therein and through an opening in the cap and an elastic washer 59 placed thereon and secured by the 105 nut 60.

From the foregoing description it is believed that the assembling and operation of my improved skylight elements will be fully and clearly understood without further description thereof.

While I have shown in detail and described the preferred embodiment of my invention and have made provision for the contingencies most likely to arise in the construction and assembling a skylight, it is to be understood that I do not limit myself to the combination in a single skylight of all the elements herein shown and described, but reserve the right to use any of such elements in 115 combination with all or any of the other elements shown and described or with parts and elements not herein shown and within the scope of my claims.

Having thus described my invention, what 125 I claim as novel, and desire to secure by Letters Patent, is—

1. In a skylight a curb composed of sheet material extending across the lower edge of the skylight-opening and bearing against a 130

plurality of metal boxes, said curb having a portion extending across the tops of said boxes which forms a glass-supporting seat, an upstanding lip formed at the lower edge of 5 said glass-supporting seat, a downwardly and rearwardly extending portion which forms a gutter, a downwardly-extending portion at the edge of said rearwardly-extending portion to form a lip which engages the edge 10 of said skylight-opening and an apron extending from said downwardly-extending lip to and upon the roof, the rear walls of said metal boxes having perforations formed therein registering with a perforation formed 15 in one of the walls of said gutter and also having openings formed in the side walls of said metal boxes.

2. In a skylight, the combination with a curb formed of sheet material and extending 20 across the lower edge of a skylight-opening, said curb being bent to form a glass-supporting seat, a gutter, a lip which engages the edge of the skylight-opening and an apron, of a plurality of metal boxes against which said 25 curb rests, said curb and said boxes being perforated to form communication therebetween and said boxes having openings formed therein leading to the roof, of gutters extending across the upper edge of the skylight-opening and along each side of the skylight-opening and communicating with the gutter of the lower curb.

3. In a skylight the combination with a gutter extending across the upper edge of 35 said skylight-opening, gutters extending along each side of the skylight-opening and gutters extending centrally of the skylight-opening and arranged beneath a central rafter-bar, of a sheet-metal curb bent to form 40 a glass-supporting seat, a gutter into which all of the above-mentioned gutters discharge, a depending lip engaging the edge of the skylight-opening and an apron extending to and upon the roof, said gutter having discharge-openings formed in one of the walls thereof, adapted to convey water from said gutter to 45 said apron.

4. In a skylight, a hollow rafter-bar having a centrally-disposed upstanding rib and 50 depending longitudinally-extending gutters, a hollow chamber disposed at the end of the rafter-bar, a curb or abutment disposed at the lower portion of the skylight to which said rafter-bar is attached, a gutter formed 55 in said lower curb, said gutter being provided with moisture-discharging openings which form a channel between said gutter and said hollow chamber, said chamber being provided with moisture-discharging openings 60 communicating with the roof.

5. In a skylight, a curb extending along the upper edge of the skylight-opening and rigidly secured to the roof, the said curb being composed of sheet material folded to

form a glass-supporting shoulder and a depending gutter, hollow boxes placed at intervals along the lower edge of the skylight and rigidly secured to the roof, the said lower curb or abutment being provided with a glass-supporting surface, a gutter extending parallel with and secured to the curb or abutment, conduits communicating with the gutter of the curb and the hollow boxes, moisture-discharging drains forming communication between the gutter and the said boxes and means for discharging moisture from the boxes to and upon the roof.

6. A skylight conforming substantially to the slant of the roof and comprising a curb extending along and rigidly secured to the upper edge of the skylight-opening, the said curb being composed of sheet material folded to form a glass-supporting shoulder and a gutter beneath the shoulder, an abutment extending along and rigidly secured to the lower edge of the skylight-opening, the said abutment being provided with a sheet of material rigidly secured thereto and folded to form a glass-supporting shoulder, an upstanding lip, a gutter, and an apron, the apron extending over and upon the roof, a rafter-bar composed of sheet material folded to form a centrally-disposed rib, glass-supporting shoulders extending laterally from the rib and gutters disposed below the shoulders, another rafter-bar composed of sheet material folded to form an upstanding rib, a glass-supporting shoulder extending laterally from the rib, a gutter disposed below the shoulder and flashing outstanding from the rib and attached to the roof, another rafter-bar composed of sheet material and having a flashing secured to a vertical wall, a glass-supporting shoulder and a gutter below the shoulder, the said rafter-bars secured at their opposite ends to the curb and the abutment and with all the glass-supporting shoulders in a single plane and all the gutters communicating, means for discharging moisture from the gutter of the abutment upon the roof, glass disposed upon the glass-supporting shoulders, a cap covering and secured to the rib of the rafter-bar and having laterally-extending skirts arranged to bear upon the glass, a counterflashing secured to the vertical wall and extending downward over the flashing of the rafter-bar and provided with a skirt bearing upon the glass and an apron secured to the roof adjacent the upper edge of the skylight-opening and extending over the glass.

In testimony whereof I affix my signature in presence of two witnesses.

HUGH A. DANIEL.
